Primary Examiner—Ian Simmons*Assistant Examiner*—Charles D Hanson(74) *Attorney, Agent, or Firm*—Foley & Lardner LLP(57) **CLAIM**

We claim the ornamental design for a double walled bowl, as shown and described.

DESCRIPTION

FIG. 1 is a top perspective view of a double walled bowl showing my new design;

FIG. 2 is a left elevation view, the right side being a mirror image;

FIG. 3 is a top plan view thereof;

FIG. 4 is a front elevation view, the rear being a mirror image;

FIG. 5 is a bottom plan view thereof;

FIG. 6 is a cross section view thereof taken along lines 6—6 of FIG. 3; and,

FIG. 7 is a cross section view thereof taken along lines 7—7 of FIG. 3.

The ornamental design which is claimed is shown in solid lines in the drawings. The broken lines in the drawings are for illustrative purposes only and form no part of the claimed design.
